Inventor:
Cromwell A. B. Halvorson, Jr.
by *Alfred S. Davis*
His Attorney.

UNITED STATES PATENT OFFICE.

CROMWELL A. B. HALVORSON, JR., OF LYNN, MASSACHUSETTS, ASSIGNOR TO GENERAL ELECTRIC COMPANY, A CORPORATION OF NEW YORK.

LIGHT FIXTURE.

Application filed September 27, 1922. Serial No. 590,982.

To all whom it may concern:

Be it known that I, CROMWELL A. B. HALVORSON, Jr., a citizen of the United States, residing at Lynn, county of Essex, State of Massachusetts, have invented certain new and useful Improvements in Light Fixtures, of which the following is a specification.

My invention relates to improvements in light fixtures for flood lighting; that is for distributing the light over a certain restricted zone or zones. Heretofore, fixtures of this kind have been made with certain elements for reflecting purposes and with certain other additional elements for refracting purposes, each separate and separately mounted and therefore calling for complicated mounting equipment. Among the objects of my invention are:—to provide an improved flood lighting device combining the reflecting and refracting elements all in one unit; to provide a device of the above general character which is simple in construction, cheap to manufacture and with simple mounting equipment; and to provide other details of improvement all of which are hereinafter more fully set forth and claimed in the accompanying specification, reference being had to the accompanying drawing in which Fig. 1 is a view in elevation of the fixture of my invention shown partially in section to more clearly illustrate the reflecting and refracting elements and their relation to the light source; Fig. 2 is an enlarged detail section of the reflector part of the unit. Referring more in detail to the drawing, it will be seen that I provide a main flaring globe holder 2 which it will be understood may be adapted to fit into any suitable standard or pendant depending upon whether the unit is to be stationary or otherwise. Within the holder is hung or secured the lamp 3 within which latter is the source of light 4. Surrounding the lamp is the globe proper which is made of glass and is one continuous piece. This globe has an upper curved sloping section 5 the outer surface of which is covered by a light reflecting silver surface 6. Depending from the reflector section 6 is an annular section 7 the outer surface of which is rippled. These ripples may be considered as irregular branching lens like ridges and depressions the function of which is to diffuse the light rays within a given zone. Sloping upwardly and toward the center of the hood

from the lower edge of the surface 7 there is a conical surface 8 the outer portion of which is also covered by a reflecting surface of silver 9. This conical surface is truncated and nestling on the top of this truncated cone there is another surface 10 concavo-convex in form the convex portion of which projects downwardly. The concave side of this surface is also rippled after the fashion of the surface 7. With the above arrangement the rays from the source of light pass through the glass section 7 and are refracted in a general downwardly direction forming an inclined conical zone of light. Certain of the rays of light are first reflected by the silver surface 6 onto the second silver surface 9 from which they are again reflected through the wall 7 as indicated by the dotted lines 11. All of the rays that pass through this wall whether they come direct or whether they are reflected, are scattered or diffused in a general downwardly inclined conical zone. Certain other of the rays of light pass directly from the source of light 4 through the concavo-convex bottom surface 10 being diffused in passing through this surface over a second conical zone the apex of which is somewhere in the neighborhood of the light. The reflecting surface may be prepared by a chemical deposit of silver 12 (Fig. 2) over which as a protection to the silver a comparatively heavy layer of copper 13 is also deposited. This copper deposit is carried over the ribs 14, 15 and 16 (Fig. 1) for the purpose of securely anchoring the deposits to the glass surface.

As shown in Fig. 1, the upper part of the globe is provided with a suitable groove 17 on the outside of the neck portion of the globe for the purpose of securing the globe to the globe holder through the medium of suitable screw's 18. As I have indicated in the drawing (Fig. 1), the upper surface 5 is curved into a parabolic surface. On the other hand, the reflecting surface 8 is a conical reflecting surface. The relation of the surfaces 6 and 8 to each other are such that all rays of light from the light source 4 that strike the surface 6 are reflected onto the surface 8 from which latter surface they are reflected through the refracting or diffusing wall 7.

It will be understood that I contemplate also making a globe which encloses the light

in two or more parts and joint them together. The sections may be put together and joined by a system of bands as is well known in the art and as practiced, for example, in connection with art glass construction. Thus, whether made in sections first and then put together to form a unit structure or whether made as a unit in the first instance, I provide a unit which serves to enclose the light source and which comprises a reflector above and a reflector below the light such that one reflector intercepts the light of the other and divides the light into a direct cone and a reflected cone, the reflected cone overlapping with and extending beyond the direct cone.

By the construction that I have described, I provide a glass unitary surface which serves as a combined reflector and refractor which is much cheaper to manufacture than the multiple element contrivances that have been heretofore used. One portion of this unitary surface serves as a reflector for directing the rays of light into particular zones, directing all of said rays through the diffusing walls in order to produce a flood lighting effect. In other words, I have provided on the same continuous surface a reflector which reflects a certain percentage of the light through another section of the same surface which diffuses the light over a particular zone. The same unit structure also receives a certain portion of the rays directly diffusing these rays over predetermined zone areas.

What I claim as new and desire to secure by Letters Patent of the United States, is:—

1. In a lighting unit a globe made in one piece with a wall in the form of a truncated cone and a concave dome at the large end of the cone, a base at the small end of the cone in the form of a truncated cone with the large end joining the wall and the small end of the base cone covered by a convex

cap, the dome and the base each being provided with a metallic reflecting surface and the wall being translucent whereby a beam of light from a source within the globe above the cap striking the dome will be reflected to the base and from the base out of the wall.

2. In a lighting unit a globe made in one piece with a wall in the form of a truncated cone and a concave dome at the large end of the cone, a base at the small end of the cone in the form of a truncated cone with the large end joining the wall and the small end of the base cone covered by a convex cap, the dome and the base each being provided with a metallic reflecting surface and the wall being translucent and provided with refracting elements whereby a beam of light from a source within the globe above the cap striking the dome will be reflected to the base out of the wall and refracted in a direction inclined to the axis of the globe and away from the dome, said cap also being translucent whereby a direct beam from the light source may pass through the cap and extend along the axis of the globe.

3. In a lighting unit, a globe made in one piece with a wall in the form of a truncated cone and a concave dome at the large end of the cone, a base at the small end of the cone in the form of a truncated cone with the large end joining the wall and the small end of the base cone covered by a convex cap, the dome and the base each being provided with a metallic reflecting surface and the wall being translucent whereby a beam of light from a source within the globe above the cap striking the dome will be reflected to the base and from the base out of the wall, said second cone projecting within the first cone.

In witness whereof, I have hereunto set my hand this 23rd day of September, 1922.

CROMWELL A. B. HALVORSON, JR.
